CONTROLLABLE PITCH PROPELLER

Frank W. Caldwell, Hartford, Conn., assignor to
 United Aircraft Corporation, East Hartford,
 Conn., a corporation of Delaware

Application October 1, 1935, Serial No. 43,006

3 Claims. (Cl. 170—163)

This invention relates to improvements in controllable pitch propellers and has particular reference to improvements in means for temporarily restraining the controlling mechanism of a controllable pitch aeronautical propeller against changing the pitch angle of the propeller.

An object of the invention lies in the provision of a light, simple and effective means for positively restraining the pitch controlling mechanism from changing the pitch angle of the propeller during the time the restraining mechanism is operative.

A further object resides in the provision of an electrically operated valve for restraining the pitch controlling mechanism of a controllable pitch propeller from changing the pitch angle of the propeller during the time the electric valve actuating mechanism is operative.

Other objects and advantages will be apparent as the description proceeds.

In the accompanying drawing in which like reference numerals refer to similar parts throughout there is illustrated a suitable mechanical embodiment of what is now considered to be the preferred form of the invention. The drawing, however, is for the purpose of illustration only and is not to be taken as limiting the invention, the scope of which is to be measured entirely by the scope of the appended claims.

In the drawing, the single figure is a vertical elevational view of a controllable pitch propeller showing the application thereto of the device of the invention, certain portions of the propeller mechanism being broken away to better illustrate the construction thereof, and the device of the invention being illustrated in section.

For a more complete disclosure of a suitable propeller mechanism with which the device of the invention may be associated, reference may be had to my co-pending application Serial No. 656,533, filed February 13, 1933, for Propellers.

Referring to the drawing in detail the numeral 10 generally indicates the front or nose plate of a suitable power plant such as a radial air cooled internal combustion engine. This front plate is provided with a bearing receiving aperture 12 through which projects a power shaft 14 upon the projecting end of which is mounted the controllable pitch propeller generally indicated at 16. This propeller has a plurality of hollow blades as indicated at 18 and 20, each blade being provided in the hollow base or root end thereof with a cylindrical flanged sleeve as indicated at 22. These sleeves are rotatably mounted upon radially projecting arms 24 and 26 formed upon a

spider having a central cylindrical portion 28 non-rotatably fixed upon the projecting end of the shaft 14. The blades are retained upon the spider arms 24 and 26 against the action of centrifugal force by means of thrust bearings as indicated at 30 which bear against the inturned ends 32 of a split barrel member 34. Arms, as indicated at 36 and 38, are non-rotatably secured to the flanged base portions of the sleeves 22 of the propeller blades 18 and 20 respectively and project forwardly from the propeller blades substantially parallel to the axis of the shaft 14. Each of the arms 36 and 38 is provided with a cam slot 40 extending therethrough for a purpose to be presently described, and each arm carries 15 upon the outer or free end thereof, a counterweight 42. These counterweights are so disposed with relation to the axes of the blades 18 and 20 and the axis of the shaft 14 about which the propeller rotates that, upon rotation of the propeller, the counterweights under the influence of centrifugal force tend to rotate the blades 18 and 20 in a direction to increase the pitch angle of the propeller blades.

A hollow piston 44 is secured upon the forward end of the cylindrical spider portion 28 so that its center line is coextensive with the projection of the axis of the shaft 14 and a cylinder 46 is mounted for reciprocation upon the piston 44 and is provided upon diametrically opposite sides 30 thereof with radially extending arms 48 which carry pins 50 which extend into the cam slots 40 provided in the counterweight arms 36 and 38 to operatively connect the reciprocable cylinder 46 with the counterweight arms so that an outward movement of the cylinder 46 with respect to the piston 44 will exert a force upon the counterweight arms opposing the centrifugal force of the counterweights 42 to rotate the propeller blades 18 and 20 toward a low pitch position. Hydraulic 40 fluid from a suitable source such as the lubricating pump of the engine, or an auxiliary pressure pump, is supplied to the space between the forward end of the piston 44 and the end wall 50 of the cylinder 46, through an axial bore in the 45 shaft 14 and through the interior of the hollow piston 44.

The engine is provided with a carburetor not illustrated, which carburetor is adjustable in the usual manner to regulating the relative proportions of air and fuel fed to the engine to maintain the fuel mixture substantially constant under changing conditions of air temperature and pressure corresponding to the various altitudes at which the engine is operated. The mixture con- 55

trolling mechanism of the carburetor is adjusted by a hand lever 54 mounted in some location convenient to the operator of the vehicle upon which the engine and propeller are mounted and connected with the carburetor by a suitable link mechanism.

The customary method of adjusting the mixture control of an internal combustion engine such as is ordinarily used for the propulsion of 10 aircraft consists in general of maintaining the engine throttle in a fixed position and then adjusting the mixture control lever until the revolutions per minute of the engine reach a maximum as indicated on a tachometer visible to 15 the operator. In some instances after the best mixture ratio has been obtained, the mixture control lever may be moved slightly toward the lean or rich positions to either provide a lean mixture to give maximum fuel economy or a 20 slightly rich mixture to prevent overheating of the engine cylinders. It is obvious that this mixture regulating operation must be carried out with a constant pitch angle setting of the propeller blades as any change in the blade angle 25 will affect the revolutions per minute of the engine so that the operator would be unable to tell at what mixture ratio the engine revolutions were at the maximum rate per minute. As the controllable pitch propeller automatically adapts its 30 blade angle to the power output of the engine to maintain constant the number of engine revolutions per minute, in order to permit accurate mixture ratio adjustment some means must be provided to maintain the propeller blade angle 35 constant during the mixture adjusting operation. In the present invention this means takes the form of a suitable solenoid actuated valve generally indicated at 58, disposed within the hollow piston 44 in a position to control the flow 40 of hydraulic fluid to and from the space between the piston and the end wall 52 of the cylinder 46. When the cylinder 46 is thus retained in fixed position relative to the piston 44, the arms 36 and 38 are restrained against movement and 45 the propeller blades 18 and 20 are held at a fixed blade angle.

The valve 58 comprises a hollow cup shaped member 60 open at its forward end and provided at its closed rearward end with a cylindrical reduced portion 62 which forms a casing for the head of the valve member generally indicated at 64. The casing member 60 is provided with an out-turned flange 66 which overlies a portion of the forward end of the piston 44 to provide 50 a bearing surface for securing the casing to the piston. Within the casing 60 there is a hollow cylindrical solenoid casing 68 enclosing a solenoid 70. The solenoid casing 68 has an outer diameter less than the inner diameter of the 55 casing 60 and is disposed within the casing 60 so that its exterior surface is annularly spaced from the interior surface of the casing 60 as indicated at 72 to provide a passage for hydraulic fluid between the solenoid casing and 60 the cup shaped casing 60. The solenoid casing 68 is provided at its rearward end with an annular extension within which is formed a beveled valve seat 74 which cooperates with a similar valve seat 76 formed on the enlarged head 65 portion of the valve 64. A plurality of ports 78 extend through the reduced portion 62 of the casing 60 and the extension on the solenoid casing to the space between the valve seats 74 and 76, and a plurality of ports 80 lead from this 70 space into the space between the solenoid cas-

ing and the cup shaped casing 60 to provide a passage through the valve mechanism for hydraulic fluid when the valve is open. A coiled compression spring 82 is disposed between an annular extension 84 upon the rear end of the valve head and the rear end of the annular extension formed on the solenoid casing 68 to resiliently urge the valve toward the open position illustrated in the drawing. The valve is provided with an integral cylindrical armature 86 which projects into a cylindrical bore provided in the solenoid casing 68 so that when the solenoid 70 is energized the armature will be moved to the left as viewed in the figure to bring the valve seats 74 and 76 into contact with each other and thus close the valve. A plate member 88 overlies the forward end of the solenoid casing 68 and the flange 66 on the casing 60, and is provided at its center with a plug 90 extending into the armature bore in the solenoid casing 20 to increase the magnetic flux within the bore. The flange 66 and the plate 88 are apertured as indicated at 89 to provide a passage for hydraulic fluid from the space 72 to the space between the piston and the cylinder. The plug 90 is provided 25 with an axial bore or aperture 92 leading into the space between the inner end of the plug and the adjacent end of the armature 86 to relieve any pressure that might build up in this space and tend to retard movements of the armature. 30 A plurality of pressure release bores 94 are also provided in the valve head to relieve any pressure that might accumulate between the valve head and the end wall 96 of the valve casing 62.

The valve is maintained in fixed relation to the piston 44 by means of a plurality of insulated screws as indicated at 98, and the solenoid leads 100 are connected to the ends of one pair of these screws at the ends thereof which project into the space between the piston 44 and the cylinder 46. Electrical leads 102 are connected to the ends 35 of these screws lying within the piston 44 and are led to respective contact rings 104 and 106 mounted in a ring 108 of insulating material secured upon the rear end of the cylindrical portion 40 of the propeller spider. The rings 106 and 108 are enclosed by an annular casing 110 rigidly secured to the front plate 10 of the engine surrounding the aperture through which the shaft 14 projects. A pair of contact brushes 112 and 114 are mounted in a block 116 of insulating material carried by the casing 110 and are spring 45 pressed into contact with the rings 104 and 106 respectively in the usual manner. A pair of electrical conductors 118 and 120 extend from the brushes 112 and 114 respectively to the opposite sides of a switch mounted upon the mixture control handle 54, one of the conduits leading 50 through a suitable source of electrical energy such as the battery 121. This switch comprises a contact button 122 secured to the knob of the mixture control handle and a leaf spring 124 provided with a contact point 126 secured to the stem portion of the handle and so positioned that the contact point 126 is in alignment with the contact button 122 but is normally spaced therefrom. The switch is ordinarily open, the solenoid 70 is deenergized and the valve 64 is urged to its open position by the spring 82, thus permitting automatic 55 regulation of the blade angle by the usual speed responsive device through which the hydraulic fluid is fed to the propeller controlling mechanism. When the operator grasps the mixture control lever 54 he incidentally bends the leaf spring 124 so that the switch contacts 122 and 60 65 70 75

126 are closed. Thus, during the time that the mixture control is being adjusted the switch is maintained closed, the solenoid 70 is energized and the valve 64 is closed so that the propeller controlling mechanism is rendered inoperative to change the blade angle of the propeller during the mixture regulating operation. When the operator releases the lever 54 the resiliency of the leaf spring 124 automatically opens the switch and restores the propeller controlling mechanism to the regulation of the speed responsive mechanism.

15 From the above description it will be observed that there has been provided a light, simple and effective mechanism for maintaining the pitch angle of the propeller against change during the mixture regulating operation incident to satisfactory engine performance.

20 While there has been illustrated and described a particular mechanical embodiment which the idea of the invention may take, it is to be understood that the invention is not limited to the particular construction so illustrated and described but that such changes in the size, shape 25 and arrangement of parts may be resorted to as come within the scope of the subjoined claims.

Having now described the invention so that others skilled in the art may clearly understand the same, what it is desired to secure by Letters 30 Patent is as follows:

What it is claimed is:

1. In a controllable pitch propeller, a rotatable hub, a plurality of propeller blades mounted on said hub for rotational adjustment about their respective axes, centrifugal means for adjusting the pitch angle of said blades in one direction, hydraulic means carried by said hub for adjusting the pitch angle of said blades in the opposite direction, means for supplying fluid under pressure to said hydraulic means from a fluid pressure

source remote from said propeller, a solenoid actuated valve carried by said hub operative to interrupt the flow of fluid to and from said hydraulic means, and a remote control means for energizing said solenoid comprising, a pair of contact rings on said hub, fixed brushes mounted adjacent to said hub to slide on said rings, a source of electrical energy, a manually operable switch, and electrical connections between said solenoid and said rings and between said brushes said source of electrical energy and said switch.

2. In a controllable pitch propeller, a rotatable hub, a plurality of propeller blades mounted on said hub for rotational adjustment about their respective axes, centrifugal means for adjusting the pitch angle of said propeller blades in one direction, hydraulic means comprising a piston fixed on said hub and a cylinder slidable on said piston operatively connected with said blades for adjusting the pitch angle of said blades in the opposite direction, a passage for fluid through said piston, a valve and a solenoid for actuating the same located in said piston to interrupt the flow of fluid through said passage, and remote control means for energizing said solenoid.

3. In a controllable pitch propeller, a rotatable hub, a plurality of propeller blades mounted on said hub for rotational adjustment about their respective axes, centrifugal means for increasing the pitch angle of said blades, hydraulic means for decreasing the pitch angle of said blades said hydraulic means comprising a piston fixed on said hub and a cylinder slidable on said piston and operatively connected with said centrifugal means, a solenoid actuated valve in said piston for controlling the movement of said cylinder by interrupting the flow of fluid to and from the space between said cylinder and said piston, and remote control means for energizing said solenoid.

FRANK W. CALDWELL. 40
